US00D973112S

(12) United States Design Patent (10) Patent No.: US D973,112 S
(45) Date of Patent: * Dec. 20, 2022

(54) PORTABLE REFRIGERATOR

(71) Applicant: Electrolux Home Products, Inc.,
Charlotte, NC (US)

(72) Inventors: Saba Rizzi, Charlotte, NC (US); Brent Curtis, Terrell, NC (US)

(73) Assignee: Electrolux Home Products, Inc.,
Charlotte, NC (US)

() Term: 15 Years

(21) Appl. No.: 29/769,511

(22) Filed: Feb. 5, 2021

(51) LOC (13) Cl. 15-07

(52) U.S. Cl.

USPC D15/81; D15/79

(58) Field of Classification Search

(57) CLAIM

The ornamental design for a portable refrigerator, as shown and described.

DESCRIPTION

FIG. 1 is a front perspective view of a portable refrigerator showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines depicting the remainder of the portable refrigerator form no part of the claimed design.

1 Claim, 6 Drawing Sheets
